UNITED STATES PATENT OFFICE.

HARRY E. WEISGERBER, OF ATLANTIC CITY, NEW JERSEY.

ROLLING-CHAIR.

SPECIFICATION forming part of Letters Patent No. 675,693, dated June 4, 1901.

Application filed December 7, 1900. Serial No. 39,007. (No model.)

To all whom it may concern:

Be it known that I, HARRY E. WEISGERBER, a citizen of the United States, residing at Atlantic City, in the county of Atlantic, State 5 of New Jersey, have invented a new and useful Improvement in Rolling-Chairs, of which the following is a specification.

My invention relates to improvements in a rolling-chair; and it consists in providing 10 such chair with screens for the wheels and adjacent running-gear as guards for preventing the contact of skirts and other garments with said wheels and adjacent parts.

It also consists of outturned fenders on the 15 lower portions of said screens, being near to the ground, so as to reliably deflect the skirt or garments of the rider from the said screen, the wheels, and adjacent portions of the running-gear, especially in getting in and out of 20 the chair.

Figure 1 represents a perspective view of a rolling-chair embodying my invention. Fig. 2 represents a perspective view taken from the bottom of a portion. Figs. 3 and 4 represent side elevations of modifications.

Similar letters of reference indicate corresponding parts in the figures.

Referring to the drawings, A designates a rolling-chair having a body B and dasher C, 30 passage-ways B' existing between said body and dasher for access to and egress from said body.

D designates gates which are hinged to the dasher C, the same being adapted to open 35 and close, thus uncovering and covering the passage-ways B', it being evident that when said gate is closed it forms a continuity of the dasher and side of the body B for concealing the feet and lower garments of the rider, 40 while also preventing wind and rain from entering the body from the side thereof.

In Fig. 3 I show the gate D' provided with pins E, which may be inserted in eyes F on the body and dasher, it being evident that 45 by raising said gate the pins leave the eyes F and the door is accordingly open.

G designates hangers constituting screens on the sides of the frame of the body below the arm-rest portions, the same approaching

the ground or road, the lower portions of said 50 hangers being swelled outwardly, forming fenders or inclosures H as guards for the wheels, said hangers preventing the passers-by from contacting with the wheels, while the fenders, owing to the swelled or segmental 55 form, deflect the garment of the rider from the wheels, it being noticed that the widest portions of said fenders are over what may be termed the "middle" of the wheels, while said fenders taper toward the floor of the 60 chair, so as to allow the garments of the rider to freely pass over the fender without obstructions of the latter both in entering and leaving the chair. In order to afford access to said wheels and gear for purposes of lubrication, cleaning, repairs, &c., said hangers are hinged to the adjacent portions of the 65 body, whereby they may be withdrawn, so as to uncover the wheels and running-gear, thus permitting access to the wheels and running- 70 gear.

If desired, the hangers may be connected with the body by sliding joints, as shown at J, Fig. 4, so that they may be moved to uncover the wheels and gear, as in the previous 75 instance.

When the hangers are in normal position, they may be connected with the adjacent member by suitable catches, so as to prevent 80 improper movement or opening of the same.

Having thus described my invention, what I claim as new, and desire to secure by Letters Patent, is—

1. A rolling-chair provided with an arm-rest, and a wheel-screen continuing downwardly from said rest and extending from side to side of the frame below said rest and swelled outwardly over the wheel.

2. In a rolling-chair, a side screen over a wheel thereof, a support for said screen and 90 a fender at the base of said screen, said fender being deflected in a direction from rear to front toward the floor of the chair.

HARRY E. WEISGERBER.
